APPARATUS FOR ATTACHING BINDER
STRINGS

Alexander G. Gordon and Joseph T. Ebert, Winston-Salem, N. C., assignors to Lillian Russell Gordon, Winston-Salem, N. C.

Application November 29, 1939, Serial No. 306,698

17 Claims. (Cl. 93—1)

This invention relates to a stringing apparatus for booklets or covers which enclose cigarette papers and the like and more especially to means for effectively and rapidly affixing a binder string to one edge thereof which can be used to hold the booklet in closed position.

In order to properly bind cigarette papers in booklet form, it is necessary to adhesively or otherwise secure one edge of all of the papers to a suitable cover. This cover is preferably crimped in such a manner that it can be wrapped entirely around the papers with its ends overlapping. When the cover has been thus folded, it is very essential that means be provided for holding the same in position to prevent the papers therein from becoming exposed while packing and shipping or while in the users' pockets.

One of the simplest securing means comprises a string, one end of which is secured to an overlapping end of the cover. The free end of this string is adapted to encircle the folded booklet and then be drawn between an intermediate portion of the string and the cover where it will be frictionally held in position to hold the booklet closed.

It is an object of this invention to provide an apparatus which will affix these binder strings in rapid succession to one edge of a continuous cover. Subsequent to this operation, the continuous cover is severed intermediate the strings so that individual covers will be formed, each cover having a string attached to one end thereof.

It is a further object of this invention to provide an apparatus for rapidly attaching one end of a string to a cover for cigarette papers, comprising means for advancing at a constant rate, a continuous cover through the machine, and means for intermittently feeding one end of a string together with an affixing stamp to the upper surface of the cover so that the stamp can adhesively secure one end of the string to the cover. After the ends of the string are affixed it is then severed so as to provide the desired length, after which the string is fed to and attached to the continuous cover, at another point in the same manner.

It is a further object of this invention to provide an apparatus of the class described having an improved means for positioning the leading end of the string on top of the cover so that the affixing stamp can be effectively pressed thereover.

Some of the objects of the invention having been stated, other objects will appear as the description proceeds when taken in connection with the accompanying drawings, in which—

Figure 1 is an isometric view of a booklet of cigarette papers embodying a cover, having an affixed string, made by the herein disclosed apparatus;

Figure 2 is an unfolded isometric view of the booklet of cigarette papers shown in Figure 1;

Figure 3 is an isometric view of the unfolded cover for the cigarette booklet shown in Figures 1 and 2, but omitting the cigarette papers;

Figure 4 is an end elevation of the machine used for attaching one end of binder strings to cigarette covers;

Figure 5 is an elevation looking at the right-hand side of Figure 4, but omitting the glue applying and tape feeding means;

Figure 6 is a vertical sectional view taken along the line 6—6 in Figure 5, showing the means for clamping one end of a binder string and an affixing stamp to the end of a cigarette cover;

Figure 7 is an elevation looking at the right-hand end of Figure 5, but omitting the tape feeding and glue applying means;

Figure 8 is a vertical sectional view taken along the line 8—8 in Figure 5, showing the cam arrangement for operating the string severing knives;

Figure 9 is a vertical sectional view taken along the line 9—9 in Figure 5, showing the cam means for operating the shuttle which feeds the string to the position where it is affixed to one end of the cover;

Figure 10 is a vertical sectional view taken along the line 10—10 in Figure 5, showing the cam arrangement for actuating the belt and top pressure rollers which clampingly engage the string, the affixing stamp, and the cover to adhesively secure these parts together;

Figure 11 is an enlarged vertical transverse sectional view taken along the line 11—11 in Figure 5;

Figure 12 is an enlarged sectional plan view taken along the line 12—12 in Figure 11;

Figure 13 is an enlarged view showing the string shuttle after it has fed one end of the string into the stripping mechanism which is disposed above the cover;

Figure 14 is an isometric view similar to Figure 13, but showing the position of the tape after the stripper and the shuttle have been drawn

a short distance away from each other to effect the straightening of the end of the string which is to be affixed to the cover;

5 Figure 15 is a view showing the string, the shuttle, and the clamping rollers after an affixing stamp has been placed in position for securing the end of the tape to the cover.

10 Referring more specifically to the drawings, the numeral 10 denotes a cover for a cigarette booklet having fold or crease lines 11, 12, 14, and 15 thereby forming sections 16, 17, 18, 19 and 20 (Figure 3). By the apparatus hereinafter to be described, one end of a string 21 is positioned above the upper side of section 20 after which a 15 stamp 22 is affixed thereto to secure the same to the cover. After this operation has been performed, a bundle of cigarette leaves 23 are adhesively secured to the section 17 which is disposed between the crease lines 11 and 12 (Figure 20 2). Then the booklet may be folded to the position shown in Figure 1 and the string 21 wrapped therearound with its free end drawn between the intermediate portion of the string and the exterior of the cover where it is frictionally held 25 in position. Figure 2 shows the booklet in an open position with the cigarette leaves therein, whereas Figure 1 shows the booklet completely closed, at which time it will be noted that the sections 16 and 20 overlap each other and are held in this overlapped position by means of the binder string which is affixed to the overlapped section 20.

30 In the manufacture of the covers 10, a continuous sheet of stock material 26 is fed at a constant rate through the apparatus (Figures 5 and 12) at which time the string 21 and the stamp 22 are affixed at spaced predetermined points. The crease lines 11, 12, 14 and 15 are placed in the stock sheet 26 prior to affixing the 35 stamp and string thereto. After the string and stamp have been attached, the stock sheet 26 is severed along lines intermediate the strings 21 such as along dot-dash lines 27 (Figure 12) 40 thereby forming the covers 10 as shown in Figure 1. The means for severing the sheet 26 along the lines 27 is not shown because the invention resides primarily in the apparatus for attaching these strings and not in the severing of the stock sheet, after the strings have been attached.

Glue applying mechanism

45 Before the stamp 22 and the string 21 are attached to the stock sheet 26 it is necessary to provide glue spots 28 to the upper side of the stock sheet at suitable spaced points. These glue spots are applied by a suitable apparatus which is schematically shown in the right-hand portion of Figure 4, said apparatus comprising a roller 50 30 above which the stock sheet 26 passes. Disposed above the roller 30 is another roller 31 having raised segments 32 on its periphery, the length of each segment or boss being substantially the same as the length of the glue spots 28. 55 These bosses contact the upper side of the stock sheet 26 as they rotate, and apply the glue thereto. During the rotation of the roller 31 the segments 32 are adapted to receive their glue from a contact roller 34, said roller 34 being adapted to have glue applied thereto from a glue roller 35. The upper periphery of the glue roller 35 is encased by a glue hopper 36 having glue 37 therein. This machine is conventional and is adapted to be driven in timed relation to the 60 70 string affixing means hereinafter to be described.

Stock sheet advancing mechanism

65 After the stock sheet of material 26 has passed through the glue applying apparatus and the glue spots have been placed thereon at the desired points, it passes over rollers 40 and 41 and then over the periphery of a sleeve 42 (Figures 5, 6 and 11). The upper peripheries of the members 40, 41 and 42 are substantially at the same elevation so as to support the lower side of the sheet 26. Disposed above the members 40, 41, and 42 and the sheet 26, is a belt 43 which is mounted around rollers 44, 45, and 46, these rollers being disposed opposite the members 40, 41 and 42, respectively.

10 The power necessary to advance the sheet of material 26 beneath the belt 43 and above members 40, 41 and 42 is supplied by the member or sleeve 42. This sleeve is rotatably mounted around a rotating shaft 47, the ends of which are 15 rotatably mounted in uprights 48 and 49, (see Figure 5) said uprights being supported by base member 50. The sleeve 42 has integral with one end thereof, a gear 51 (see Figures 5 and 12), which meshes with another gear 52 on a shaft 25 53. This shaft 53 has its ends rotatably mounted in upright 48 and in a bearing plate 54. Also fixedly secured upon shaft 53 is a spiraled gear 55 which is driven by another spiraled gear 56 on shaft 57 therebelow. The shaft 57 is driven 30 continuously by a suitable source of power. It is seen that the rotation of shaft 53 in Figures 4 and 5 will cause the gears 51 and 52 to rotate the sleeve 42 in a clockwise direction in Figure 11 to continuously advance the stock sheet 26 through 35 the apparatus.

Top roll lifting and lowering mechanism

40 The end of string 21 is positioned above the top of the stock sheet 26 at a point directly between the rollers 40 and 44 (Figures 6, 11 and 12). In order to properly position the string relative to the sheet as it travels through the machine, it is necessary to provide means for raising the rollers 44 and 45 so that a gap, as shown in Figure 6, will be provided between the lower side of the belt 43 and the upper sides of the rollers 40 and 41. After the end of string 21 and the stamp 22 have been properly positioned, the belt 43 and the rollers 44 and 45 are lowered to the position 45 shown in Figure 11 to press the parts in contact with each other. The portion of belt 43 which is beneath the roller 46 will not be raised during normal operation of the machine because the stock sheet must be held against the driving 50 sleeve 42. The means for raising and lowering the belt 43 and the rollers 44 and 45 to provide this space for positioning the stamp and the string on top of the stock sheet comprises a lever arm 58 which supports the rollers 44 and 45. 55 This lever arm is loosely secured around a shaft 59 by means of an attached sleeve 60 (Figures 5, 6, 10 and 11). When it is desired to form the above mentioned space by raising the rollers 44 and 45 together with a portion of the belt 43, it 60 is necessary to rotate the sleeve 60 together with the attached lever 58 in a clockwise direction in Figures 6 and 10 and 11 thereby causing the desired space to be provided so that the end of a 65 shuttle, hereinafter to be described, can move 70 between the lower side of the belt 43 and the upper side of the sheet of material 26.

75 Sleeve 60 has integral therewith a bell crank 61 having rollers 62 and 63 on the free ends which contact cams 64 and 65 respectively. Cams 64 and

65 are fixedly secured on the shaft 47. As the shaft 47 rotates the cams 64 and 65 will oscillate the sleeve 60 as well as the arm 58 to cause the rollers 44 and 45 together with the belt 43 to be raised and lowered at the proper times during the application of the string 21 and the stamp 22 to the stock sheet.

String feeding mechanism

10 As the glue spots 28 on the stock sheet 26 pass through the machine a suitable mechanism is adapted to operate in timed relation to the movement of the stock sheet to position one end of string 21 directly over the glue spots so that a 15 stamp can be subsequently placed thereover to secure the same in position. Figures 5, 12, 13 and 14 and 15 show this mechanism in detail. It is here seen that a suitable shuttle 67 is provided which has an arcuate slot 68 therein through 20 which the string passes. This slot has an enlarged cavity 68a communicating therewith in which a pivoted dog 69 is mounted, said dog having a serrated point for engaging the intermediate portion of the string 21 to prevent it from 25 slipping relative to the slot whenever the shuttle moves downwardly to position the end of the string on the top of a glue spot 28. This dog 69 normally is held in engagement with the string by means of a suitable compression spring 70.

30 The shuttle 67 is secured to an arm 72, which arm has its upper end fixedly secured around a shaft 73, said shaft being rotatably mounted in a bracket 74 which, in turn, is secured to the end frame 48. Also secured upon the shaft 73 (Figure 11) and adjacent the member 72 is a gear 76 which normally meshes with a vertically disposed rack 77 and this rack is mounted for vertical sliding movement in raceway 78. It is evident that when the rack 77 is moved downwardly to the position shown in Figure 5 that the lower end of the shuttle 67 will advance the end of the string 21 to a position above a glue spot on the top of sheet 26 and within the space between the separated rollers 40 and 44 (Figure 6).

45 The lower end of the rack 77 is pivotally secured as at 79 to a link 80 which in turn is pivoted as at 80a to a lever 81, said lever having its other end fixedly secured to a shaft 82, the ends of which are mounted in upstanding members 48 and 49. Integral with the lever 81 and loosely mounted around the shaft 82 is a sleeve 83, said sleeve having lever arms 85 and 86 also extending therefrom (see Figures 5 and 9). These lever arms have rollers 87 and 88 on the free ends 55 thereof which contact cams 89 and 90 respectively, which cams are fixedly secured on shaft 47. As shaft 47 rotates the cams serve to raise and to lower the rack 77 which actuates the shuttle 67 at the proper time. Of course when the roller 88 is on the high side of the cam 90 the shaft 82 has been rotated in such a manner as to cause the rack 77 to be lowered and at the same time to advance the shuttle 67 and the projecting string 21 substantially to the position shown in Figures 5 and 13. On the other hand, when the roller is on the low side of the cam 90, the roller 87 is on a high side of cam 89 at which time the rack and shuttle have been returned to uppermost position.

70 The string 21 is severed from a continuous strand 21a which is drawn through an eyelet 95 immediately before it passes into the shuttle 67. This eyelet is positioned in such a manner that upon the movement of the shuttle and the rack 77 to uppermost position, the string 21 will be drawn between a pair of shearing knives 96 and

97 to be later described so that at the proper time these knives can be actuated to sever the string.

The strand 21a is drawn from a package 99, which package is rotatably mounted upon a bolt 100. In order to apply the proper tension to the face of this package, a washer 101, a spring 102, and a nut 103 are provided. After leaving the package 99 the strand 21a passes downwardly through a guide tube 106 and around friction feed 10 roller 107, then through an eyelet 108, and then upwardly through an eyelet 109 on the end of a pivoted wire 111. This wire 111 is normally rotated in a clockwise manner in Figure 5 by any suitable means such as the torsion spring 112 (see Figures 4 and 7). From the eyelet 109 the strand passes through eyelet 95 previously described.

The friction feeder roller 107 (Figures 4 and 5), is rotated in timed relation to the machine so as to feed the strand 21a constantly from the package 99 to the shuttle 67. Figure 4 shows the means for producing the constant feeding action. It is here seen that the roller 107 is fixedly secured on one end of a shaft 115 which is rotatably mounted in bracket 116 secured to the upstanding member 48. The other end of the shaft 115 has a spiraled gear 117 fixedly secured thereon which meshes with a spiraled gear 118 on shaft 119. Also secured on shaft 119 is gear 120 meshing with another gear 121 fixedly secured on shaft 53. It is therefore seen that through the gears 121, 120, 118 and 117 and the shaft 115, the feeder roller 107 is rotated in timed relation to the other parts of the machine to feed the strand 21 to the shuttle 67.

Tape feeding mechanism

As heretofore stated, it is also necessary to simultaneously position a suitable stamp directly above the glue spot 28 and above the end of the positioned string 21 substantially at the same time that the end of the string is placed in position. The stamp 22 which is shown secured to the cover in Figures 2 and 3, formerly comprised a portion of an elongated tape. This tape will be designated by the reference character 22a. This tape in Figure 5 has a suitable dry adhesive 125 on one side thereof, which, when contacted by a moist surface will adhere thereto. The tape 22a is drawn from a suitable roll 126, said roll being rotatably mounted around a bolt 127 extending from the upstanding end frame 48. A spring 128 together with a nut 129 is used to apply the proper friction to the roll as the tape 22a is being drawn therefrom.

Tape 22a passes downwardly between a pair of feed rolls 130 and 131 (Figures 4 and 11), and then beneath the roller 131 and around another feed roll 132. By referring to Figure 11, it will be seen that the roller 132 has a serrated portion 133 on only a portion of its circumference. The length of this serrated portion is substantially the same as the length of stamp 22. The tape 22a also passes beneath the roller 132 and above another serrated roller 134. When the serrated portion 133 of roller 132 passes into engagement with the periphery of serrated roller 134, the tape 22a is tightly gripped and is caused to advance until a length of tape equal to the length of the serrated portion 133 is drawn downwardly. After the serrated area 133 passes over roller 134, there is no friction between the rollers 132 and 134 and tape 22a; consequently no tape will be fed until roller 132 makes substantially

another revolution. The roller 132 is fixedly secured upon a shaft 135 which extends through the supporting framework 136 for the above-mentioned rollers 130, 131, 132 and 134. The 5 projecting end of the shaft 135 fits into squared cavity 137 of another shaft 138 (Figures 4, 5, and 7). This shaft has a gear 139 fixedly secured thereon which meshes with another idler gear 140, said idler gear 140 also meshing with a gear 10 121 in shaft 53 previously described. It is therefore seen that as the shaft 53 rotates that the shaft 138 and 135, together with roller 132 will likewise rotate and upon each rotation of the roller 132 the serrated area 133 will advance the 15 end of tape 22a on top of the end of string 21.

Since the tape 22a is in a continuous length it is necessary to provide means for severing the same at the proper time so that the stamp 22 can be provided for each individual cover. Figure 20 11 shows the means which is employed for effecting this severing operation. It is here seen that a shaft 145 is provided upon which is mounted a bell crank 146, one leg of said bell crank having a roller 147 on its free end which is 25 adapted to ride upon a cam 148 on shaft 135. This cam has a high place 150 thereon, which, when contacted by the roller 147 will cause the bell crank to rotate in a clockwise direction. The other leg of the bell crank 146 has mounted 30 thereon as at 152, a blade 153, said blade being held against a stationary guide 154 by any suitable means such as a tension spring 155. A stationary shearing member 156 is disposed opposite member 154 and this member 156 also operates with member 154 in directing the end 35 of tape 22a to the proper position before it is severed.

In order to normally hold the roller 147 against the periphery of cam 148, a suitable tension 40 spring 157 is provided. Since the feeding roll 132 for the tape is driven from the driving gear 55, which gear also drives the stock sheet feeding mechanism, and the tape and string feeding mechanism, it is seen that the parts are all 45 moved in timed relation to each other. The bell crank 146 is oscillated to cause the blade 153 to shear the lower end of the tape 22a off at the proper time and to allow it to fall at the proper time onto the string 21 and glue spot 28 to be 50 moved along therewith to be engaged by the lower side of the belt 43 which belt presses it upon the string 21 and the glue spot 28.

It will be noted by referring to Figures 5 and 13 that when the shuttle has reached its lower 55 most position while advancing the end of the strand 21a, that the projecting end of the strand is doubled backwardly in substantially a parallel position to the end of the shuttle. It is essential that the end of this string be straightened to 60 point away from the shuttle so that it can be properly positioned upon the top of the stock sheet 26 prior to applying a stamp 22 thereon. As will be seen in the drawings, a suitable stripper 65 160 advances towards the shuttle simultaneously with the advance of the shuttle. In other words, upon each operation, the stripper 160 moves to the left (Figure 5) whereas the shuttle 67 moves to the right and when the two meet each other, the leading end of the shuttle penetrates a slot 161 in the upstanding leg of the stripper member. The stripper member also has a bridge 162 at the lower portion of the slot 161 and this bridge member serves to separate slot 161 from a second slot 163, in the horizontal portion 70 of the stripper. Whenever the parts have

reached a position as shown in Figure 13 the direction of travel for each member is reversed, and as a result the members move away from each other. Upon this reverse movement the leading end of the doubled strand 21a falls downwardly into the slot 163 and beneath the bridge member 162. Upon farther backward travel of the shuttle and stripper, the strand is straightened out on top of the bridge 162 in the manner shown in Figure 14. The parts continue to separate from each other until they are in the position shown in Figure 15, at which time the end of the strand 22a overlaps the edge of the stock sheet 26 a substantial amount. It is while the end of the strand is in this position, that the 15 stamp 22 is affixed on the upper side thereof at a point where the glue spots 28 are positioned.

The means for moving the stripper member 160 toward and away from the shuttle comprises a rod 170, said rod being mounted for reciprocatory movement in upstanding member 49. The other end of the rod 170 has pivotally secured thereto as at 171, a down-standing lever 172 and the intermediate portion of this lever has a roller 173 secured thereto which contacts the face of a cam 174. This cam is fixedly secured upon the end of shaft 47. The lower end of the lever 172 is pivoted as at 175 to the base 50. In order to normally hold the roller 173 in contact with the cam 174, a suitable compression spring 176 is mounted 30 around the rod 170, at a location between the stripper 160 and the end frame 49. However, when the roller 173 rides upon the high side of the face cam 174, the stripper member 160 will be moved to the extreme right hand position in 35 Figure 5.

The face cam 174 is rotated by means of shaft 47, said shaft being rotatably mounted in upstanding members 48 and 49, previously described. The other end of this shaft has a 40 pinion 180 fixedly secured thereon, which pinion also meshes with the gear 121 thereabove. Immediately upon the straightening of the end of strand 21a upon the glue spot 28 in the manner shown in Figure 15, the adhesive stamp 22 is 45 severed from the end of tape 22a. Thereafter, the rollers 44 and 45 are caused to move downwardly from the position shown in Figure 6 to the position shown in Figure 11, where the stamp 22, the end of strand 21a, and the stock sheet 26 50 are pressed together. The mechanism for causing these rollers to be moved downwardly, to the position shown in Figure 7, has been previously described in connection with the cam mechanism 55 shown in Figure 10.

Whenever the rollers 40, 41, 44 and 45, and belt 43 grip the stamp 22 and the strand 21a and the sheet material 26, the shuttle 67 immediately turns to its uppermost dotted line position as shown in Figure 5. During this upward 60 movement the end of the strand is gripped by the above-named belt and rollers against the upper surface of the stock sheet 26. The shuttle will therefore slide relative to the string causing the length of string between the end of the shuttle and the edge of the sheet 26 to be increased to several inches. Also while the shuttle returns to dotted line position the strand is positioned in between the shearing knives 96 and 97. 65

Strand clipping apparatus

With one end of the strand clamped upon sheet 26 below the belt 43 and above the rollers 40 and 41, and above the sleeve 42, and with the shuttle 67 holding the intermediate portions thereof, be- 70 75

tween the shearing blades 96 and 97, the next operation to be performed is the clipping of the strand. This clipping is effected by rotating the movable blade 96 in a counter-clockwise manner about its pivot point 180 (Figures 7 and 11) to thus cause this movable blade to pass in close proximity to the stationary blade 97 and shear the strand.

The movable blade 96 is secured on the free end of a lever arm 18. The other end of the lever arm 18 has pivoted thereto as at 182 a vertically disposed link 183, said link having its lower end pivoted as at 184 to an arm 185. The arm 185 is fixedly secured upon the shaft 59, which in turn is mounted for oscillation in the upstanding members 48 and 49 previously described. Also fixedly secured upon the shaft 59 is a bell crank 187, one leg of which has a roller 188 thereon for engaging a cam 189 and its other leg having a roller 190 thereon for engaging a cam 191. Both cams 189 and 191 are fixedly secured upon shaft 47. The shape of these cams is such as to effect the raising and lowering of the movable knife 96 to shear the strand 21a at the proper time thereby leaving a string 21 attached to sheet 26. It will be noted that the strand is sheared so that a short length thereof will be left projecting beyond the end of the shuttle and this projecting end is that portion which is adapted to be straightened upon the next operation with the stripper mechanism which is shown in detail in Figures 13, 14 and 15.

String removing apparatus

After the string has been sheared as described in the preceding operation, it is necessary to provide means for moving the string in the same direction as the stock sheet 26 is moving through the machine so as to prevent the severed end from becoming entangled with the shuttle and other moving parts upon the next operation. This removing operation is effected by a hook member 195 which is an integral part of a rack bar 196. This rack bar has suitable teeth in the lower side thereof which mesh with a gear 197 on shaft 198. Also fixedly secured upon the shaft 198 is a smaller pinion 199 which meshes with a set of rack teeth 200 on the rack bar 17, previously described. Whenever the rack bar 17 moves downwardly to cause the shuttle to advance the end of the strand 21a over the glue spot 28, the teeth 200 in this same rack bar cause the pinions 197 and 199 to rotate, which, in turn, will move the bar 196 and its associated hook 195 to the right at a speed considerably faster than the normal travel of the stock sheet 26. This movement of the bar will cause the loose ends of the string 21 to be moved forwardly so that it will be out of the way of the mechanism during its next operation of applying a string and a stamp to one of the glue spots.

Upon the return of the shuttle to uppermost position the hook 195 and its associated rack bar 196 will simultaneously move to the left in Figure 11 so that the hook will be disposed behind the next succeeding string which is at that time being attached to the top of the stock sheet 26. Of course when the shuttle is again withdrawn and the strand severed this hook 195 will again move to the right and engage this string to move it to the right in the same manner as the preceding string was moved. In order to prevent this string and the labels from becoming entangled with the rack and gear members, a suitable guide member 205 is provided which serves to house the gears 197 and 199 as well as the rack member 196. This 75 guide is supported by the base member 50.

Supporting means for the stock sheet

It is very essential that the stock sheet 26 be sufficiently supported on its lower side beneath the glue spot 28 when a strand and stamp are being affixed thereto. In order to provide a supporting means between the rollers 40 and 41 at a suitable distance from the edge of the stock sheet 26, a suitable plate 206 has been provided (Figures 5, 6, 11 and 15), the lower end thereof, being secured around shaft 198 and its upper end fitting into a groove 40a in roller 40. The right hand end of the plate 206 rests in close proximity to the periphery of the roller 41 and the upper edge of the plate 206 is flush top with the rollers so that it will support the lower portion of stock sheet 26. Therefore, the pressure exerted by the belt 43 and the rollers 44 and 45 will be sufficiently resisted to cause the stamp 22 to thoroughly secure the end of the strand 21 to the glue spot.

By referring to Figures 5 and 15, it is seen that the roller 40 has a restricted portion 40b integral with its right-hand end. The purpose of providing the portion 40b is to have a rim against which the lower side of the sheet 26 is pressed by the downward pressure of the rollers thereabove. This rim will serve to imbed itself slightly into the bottom of the stock sheet 26 and cause a slightly greater pressure to be exerted along a line parallel to the edge of the stock sheet, and thereby serve to more firmly affix the stamp 22 to the glue spots along this line.

Top roll pressure relieving mechanism

It is often desirable to release the pressure that the top roller 46 exerts upon the stock sheet 26 and the sleeve 42 therebelow. By referring to Figure 11, it is seen that the roller 46 is rotatably mounted on the left-hand end of a lever 212, said lever being mounted for oscillation around shaft 59 previously described. The upper right hand end of the lever 212 is adapted to be engaged by an eccentric 213 pivoted as at 214 to the upstanding end member 48. Integral with this eccentric is a lever 215. When it is desired to release the pressure exerted by the roller 46, it is only necessary to rotate this eccentric in a clockwise direction in Figure 11 and this action will cause the left-hand end of lever 212 to raise the roller 46 and the belt 43 out of contact with the upper part of the stock sheet 26. This operation is necessary when the stock sheet is being initially positioned between the rollers, or when it is desired to entirely remove a stock sheet from the apparatus. A suitable tension spring 216 is provided for normally causing the roller 46 to exert a downward pressure upon the stock sheet 26 and the sleeve 42 therebelow.

The method of operation of the apparatus is substantially as follows: First the stock sheet 26 with the moist spots of glue 28 applied thereon is advanced toward the rollers 44, 45, 46, 40 and 41 and toward the sleeve 42. At this time the rollers 44 and 45 are raised so that only that portion of the belt 43 between the roller 46 and sleeve 42 will clamp the stock sheet 26. As the moist glue spot gets between the rollers 40 and 44, the shuttle 61 advances the strand 21a and at the same time, the stripper 160 is moved toward the shuttle to engage the end of the strand. Then both the shuttle and the stripper withdraw from each other thereby effecting a straightening operation of the string so that it will lie flat on top of the glue spot 28. When the glue spot 28 passes beneath this strand, a gummed tape 22a is advanced over the strand, which tape is sheared 75

just as the rollers 44 and 45 together with a portion of the belt 43, are lowered into clamping engagement with the sheared stamp and the end of the strand. After the shuttle has retired to 5 substantially the position shown in Figure 15, it temporarily halts until the clamping rollers engage the string and the severed stamp. The shuttle, then retires all the way to uppermost dotted line position as shown in Figure 5, after 10 which the string is severed at a point slightly beyond the tip of the shuttle. The severed attached string is then engaged by the hook or kicker member 195 and is moved in the same direction as the stock sheet 26 is travelling but 15 at a substantially greater rate of speed. This kicking operation is provided to get the loose end out of the way of the parts for the next operation.

In the drawings and specification, there has 20 been set forth a preferred embodiment of the invention, and although specific terms are employed, they are used in a generic and descriptive sense only and not for purposes of limitation, the scope of the invention being set forth in the 25 appended claims.

We claim:

1. Apparatus for cutting a piece of strand from a strand supply and attaching the piece of strand to a booklet cover comprising means for rendering adhesive an area on the cover, means for advancing the cover through said apparatus, means for depositing one end of said strand upon said adhesive area, means for simultaneously cutting a stamp from a strip of material and 35 allowing it to fall upon the end of the strand and upon the adhesive area, and means for severing the strand at a point removed from the adhesive spot thereby leaving an attached string to the cover.

40 2. Apparatus for attaching a string to a booklet cover, comprising a shuttle through which the string is adapted to pass and project a substantial distance beyond the end thereof, means for rendering adhesive an area on the cover, means 45 for advancing said shuttle to position said projecting string in overlapping relation to said cover and said adhesive area, means for holding the end of the string intact with the cover, and means for withdrawing the shuttle from the cover 50 while said string is so held.

3. Apparatus for attaching pieces of strands from a strand supply to a booklet cover, comprising a shuttle through which the strand is adapted to pass and project a substantial distance beyond 55 the end thereof, means for advancing said cover through the apparatus, means for rendering spaced areas on the cover adhesive as the cover advances, means for successively advancing the shuttle to position a projecting strand in overlapping relation to said cover and said adhesive areas, means for clamping the overlapped end 60 of the strand to hold it intact with the cover, means for withdrawing the shuttle from the cover while the strand is thus clamped and means for 65 severing the strand at a point substantially removed from the shuttle whereby an attached string will be left with the cover and one end of the strand will project beyond the end of the shuttle for the next operation.

70 4. Apparatus for attaching pieces of strand from a strand supply to a booklet cover comprising a shuttle through which the strand is adapted to pass and project a substantial distance beyond 75 the end thereof, means for advancing said cover through the apparatus, means for rendering

spaced areas on the cover adhesive as the cover advances, means for advancing the shuttle and projecting strand to an overlapping relation to said cover and said adhesive areas, a stripper mechanism and means for advancing the same in 5 overlapping relation to the shuttle and projecting strand, means for simultaneously withdrawing said stripper and shuttle away from each other to cause the projecting strand to be straightened above said cover, means operable 10 upon the withdrawal of the shuttle and the stripper for clamping the overlapped end of the strand intact with the cover and adhesive area while the shuttle continues to withdraw, and means for severing the strand at a point substantially removed from the shuttle, whereby an 15 attached string will be left with the cover, and one end of the strand will project beyond the end of the shuttle for the next operation.

5. Apparatus for cutting a piece of strand from 20 a strand supply and attaching the piece of strand to a booklet cover comprising a shuttle through which the strand is adapted to pass and project a substantial distance beyond the end thereof, means for advancing said cover through the apparatus, means for rendering spaced areas on 25 the cover adhesive as the cover advances, means for successively advancing the shuttle to position a projecting strand in overlapping relation to said cover and said adhesive areas, means for severing a stamp from one end of a strip of material and allowing it to fall upon the overlapped end of the strand and upon said adhesive area, means for clamping the overlapped end of the strand and superposed stamp to hold it intact with the 30 cover, means for withdrawing the shuttle from the cover while the strand is thus clamped and means for severing the strand at a point substantially removed from the shuttle whereby an attached string will be left with the cover and 35 one end of the strand will project beyond the end of the shuttle for the next operation.

6. Apparatus for cutting a piece of strand from a strand supply and attaching the piece of strand to a booklet cover comprising a shuttle through 45 which the strand is adapted to pass and project a substantial distance beyond the end thereof, means for advancing said cover through the apparatus, means for rendering spaced areas on 50 the cover adhesive as the cover advances, means for advancing the shuttle and projecting strand to an overlapping relation to said cover and said adhesive areas, a stripper mechanism and means for advancing the same in overlapping relation to the shuttle and projecting strand, means for 55 simultaneously withdrawing said stripper, and shuttle away from each other to cause the projecting strand to be straightened above said cover, means for severing a stamp from one end of a strip of material and allowing it to fall upon 60 the overlapped end of the strand and upon said adhesive area, means operable upon the withdrawal of the shuttle and the stripper for clamping the overlapped end of the strand and superposed stamp intact with the cover and adhesive 65 area, while the shuttle continues to withdraw, and means for severing the strand at a point substantially removed from the shuttle, whereby an attached string will be left with the cover 70 and one end of the strand will project beyond the end of the shuttle for the next operation.

7. Apparatus for attaching pieces of strand from a strand supply to a booklet cover comprising a shuttle through which the strand is adapted to pass and project a substantial distance 75

- beyond the end thereof, means for advancing said cover through the apparatus, means for rendering spaced areas on the cover adhesive as the cover advances, means for successively advancing the shuttle to position a projecting strand in overlapping relation to said cover and said adhesive areas, a pair of flush-top rollers disposed beneath said cover and having a bridge therebetween which bridge is also flush-top with the rollers, a second pair of rollers disposed above said first-named rollers, a rubber belt encircling said second rollers, means for clamping the belt against the overlapped end of the strand to hold it in contact with the cover while it travels the distance between the bottom rollers, means for withdrawing the shuttle from the cover while the strand is thus clamped and means for severing the strand at a point substantially removed from the shuttle whereby an attached string will be left with the cover and one end of the string will project beyond the end of the shuttle for the next operation.
8. Apparatus for attaching pieces of strand from a strand supply to a booklet cover comprising a shuttle through which the strand is adapted to pass and project a substantial distance beyond the end thereof, means for advancing said cover through the apparatus, means for rendering spaced areas on the cover adhesive as the cover advances, means for advancing the shuttle and projecting strand to an overlapping relation to said cover and said adhesive areas, a stripper mechanism and means for advancing the same in overlapping relation to the shuttle and projecting strand, means for simultaneously withdrawing said stripper and shuttle away from each other to cause the projecting strand to be straightened above said cover, means for releasing a stamp to allow it to fall upon the overlapped end of the strand and upon said adhesive area, a pair of flush-top rollers disposed beneath said cover, and having a bridge therebetween which bridge is also flush-top with the rollers, a second pair of rollers disposed above said first-named rollers, a belt encircling said second rollers, means operable upon the withdrawal of the shuttle and the stripper for pressing the lower surface of the belt against said stamp, overlapping strand and cover while the shuttle continues to withdraw, and means for severing the strand at a point substantially removed from the shuttle, whereby an attached string will be left with the cover and one end of the strand will project beyond the end of the shuttle for the next operation.
9. Apparatus for securing one end of a strand to a booklet cover having adhesive spots thereon, comprising means for advancing said cover longitudinally thereof through said apparatus, a shuttle adapted to carry said strand, means for severing the end of the strand at a point substantially in advance of the shuttle tip, means for oscillating the tip of the shuttle transversely of the cover and in timed relation to its travel to position the projecting end of said strand above one of said glue spots, a stripper mechanism mounted for reciprocation laterally of said cover and being oppositely disposed to said shuttle, means for advancing said stripper mechanism toward said advancing shuttle, until the projecting string is engaged by the stripper, means for simultaneously withdrawing both the stripper and shuttle to straighten the projecting string above one of said adhesive spots, means for clamping said end upon said spot.
10. Apparatus for securing one end of a strand to a booklet cover having adhesive spots thereon, comprising means for advancing said cover longitudinally thereof through said apparatus, a shuttle adapted to carry said strand, means for severing the end of the strand at a point substantially in advance of the shuttle tip, means for oscillating the tip of the shuttle transversely of the cover and in timed relation to its travel to position the projecting end of said strand above one of said glue spots, a stripper mechanism mounted for reciprocation laterally of said cover and being oppositely disposed to said shuttle, means for advancing said stripper mechanism toward said advancing shuttle, until the projecting string is engaged by the stripper, means for simultaneously withdrawing both the stripper and shuttle to straighten the projecting string above one of said adhesive spots, means for feeding a stamp upon said projecting end and upon said spot, and means for clamping said stamp and said end upon said spot.
11. Apparatus for attaching one end of a string to one edge of a continuous strip which is adapted to be cut into separate covers for cigarette paper booklets, comprising means for advancing the strip and applying pressure thereto for a substantial space, means for applying spaced adhesive spots to the strip, a source of string, a member for carrying the string and feeding the end portion thereof onto the adhesive spots one at a time, means for positioning the end of the string at substantially right angles to the edge of the strip, means for raising a portion of the advancing means out of contact with the strip while the string is applied to the strip, means for releasing labels to allow the same to fall onto the ends of the string and means for lowering the portions of the advancing means into contact with the strip to apply pressure to the label and the end of the string to cause the same to adhere to the strip.
12. Apparatus for attaching one end of a string to one edge of a continuous strip which is adapted to be cut into separate covers for cigarette paper booklets, comprising means for advancing the strip and applying pressure thereto for a substantial space, means for applying spaced adhesive spots to the strip, a source of string, a member for carrying the string and feeding the end portion thereof onto the adhesive spots one at a time, means for positioning the end of the string at substantially right angles to the edge of the strip, means for raising a portion of the advancing means out of contact with the strip while the string is applied to the strip, means for releasing labels to allow the same to fall one at a time onto the end of the string, means for lowering the portions of the advancing means into contact with the strip to apply pressure to the label and the end of the string to cause the same to adhere to the strip, and means for supporting the strip on the side opposite to the lowered advancing means to insure proper pressure being applied to the label and the strip after the string and label have been applied thereto.
13. In apparatus for making wrappers for cigarette paper booklets from a continuous strip which is pre-creased for forming a plurality of connected booklets, a plurality of rollers for supporting the lower surface of the strip, a pair of upper rollers disposed above the plurality of rollers and having a belt thereon for applying pressure to the upper side of the strip, means for driving some of the rollers to advance the sheet,

- means for raising intermittently one of the upper rollers and one end of the belt carried thereby, means for applying a spot of adhesive to each booklet cover, means for supporting a package of string, means for feeding one end of the string into contact with an adhesive spot while the belt is raised, means for severing a length of string from the package, means for straightening the end of the string to position it on the cover at approximately right angles to the edge of the strip, means for releasing a label and allowing it to fall onto the end of the string and the adhesive spot, means for then lowering the belt to apply pressure to the label and string as it travels farther through the apparatus, means for additionally supporting the lower surface of the strip while the applied label and string are moving beneath the belt, and means for moving the free end of the attached string in the same direction as the strip travels but at a faster rate whereby the string will be moved out of the path of the string feeding means prior to the next operation.
14. Apparatus for securing one end of a strand to a booklet cover having adhesive spots thereon, comprising means for advancing said cover longitudinally thereof through said apparatus, a shuttle adapted to carry said strand, means for severing the end of the strand at a point substantially in advance of the shuttle tip, means for oscillating the tip of the shuttle transversely of the cover and in timed relation to its travel to position the projecting end of said strand above one of said glue spots, a stripper mechanism mounted for reciprocation laterally of said cover and being oppositely disposed to said shuttle, means for advancing said stripper mechanism toward said advancing shuttle, until the projecting string is engaged by the stripper, means for simultaneously withdrawing both the stripper and shuttle to straighten the projecting string above one of said adhesive spots, means for releasing a stamp and allowing it to fall upon said projecting end and upon said spot, means for applying pressure to said stamp and string for a substantial distance of travel after they are applied, and means for raising the pressure applying means out of contact with the strip while a string and stamp are applied to each succeeding booklet cover.
15. Apparatus for securing one end of a strand to a booklet cover having adhesive spots thereon, comprising means for advancing said cover longitudinally thereof through said apparatus, a shuttle adapted to carry said strand, means for severing the end of the strand at a point substantially in advance of the shuttle tip, means for oscillating the tip of the shuttle transversely of the cover and in timed relation to its travel to position the projecting end of said strand above one of said glue spots, a stripper mechanism mounted for reciprocation laterally of said cover and being oppositely disposed to said shuttle, means for advancing said stripper mechanism toward said advancing shuttle until the projecting string is engaged by the stripper, means for simultaneously withdrawing both the stripper and shuttle to straighten the projecting string above one of said adhesive spots, and advancing means comprising a belt supported by a pair of spaced rollers, means for raising one of the rollers and one end of the belt out of contact with the cover and holding the same in elevated position while the string is fed to the adhesive spot and again

lowering said roller and its belt into contact with the booklet cover to apply pressure thereto for a substantial distance of travel of the booklet after the string is applied thereto.

16. Apparatus for attaching pieces of strand from a strand supply to a booklet cover comprising a shuttle through which the strand is adapted to pass and project a substantial distance beyond the end thereof, means for advancing said cover through the apparatus, means for rendering spaced areas on the cover adhesive as the cover advances, means for advancing the shuttle and projecting strand to an overlapping relation to said cover and said adhesive areas, a stripper mechanism and means for advancing the same in overlapping relation to the shuttle and projecting strand, means for simultaneously withdrawing said stripper and shuttle away from each other to cause the projecting strand to be straightened above said cover, means for releasing a stamp and allowing it to fall upon the overlapped end of the strand and upon said adhesive area, a pair of flush-top rollers disposed beneath said cover and having a bridge therebetween which bridge is also flush-top with the rollers, a second pair of rollers disposed above said first-named rollers, a belt encircling said second rollers, means for raising one of the second pair of rollers and its belt while the shuttle and the stripper mechanism and the stamp depositing means are operating, means operable upon the withdrawal of the shuttle and the stripper for pressing the lower surface of the belt against said stamp, overlapping strand and cover while the shuttle continues to withdraw, and means for severing the strand at a point substantially removed from the shuttle, whereby an attached string will be left with the cover and one end of the strand will project beyond the end of the shuttle for the next operation.
17. Apparatus for attaching pieces of strand from a strand supply to a booklet cover comprising a shuttle through which the strand is adapted to pass and project a substantial distance beyond the end thereof, means for advancing said cover through the apparatus, means for rendering spaced areas on the cover adhesive as the cover advances, means for successively advancing the shuttle to position a projecting strand in overlapping relation to said cover and said adhesive areas, a pair of flush-top rollers disposed beneath said cover and having a bridge therebetween, which bridge is also flush-top with the rollers, a second pair of rollers disposed above said first-named rollers, a rubber belt encircling said second rollers, means for raising one of the second pair of rollers and one end of the belt from contact with the booklet cover while the shuttle places the strand in contact with the adhesive spot, means for clamping the belt against the overlapped end of the strand to hold it in contact with the cover while it travels the distance between the bottom rollers, means for withdrawing the shuttle from the cover while the strand is thus clamped and means for severing the strand at a point substantially removed from the shuttle whereby an attached string will be left with the cover and one end of the string will project beyond the end of the shuttle for the next operation.

ALEXANDER G. GORDON.
